DESIGN FOR A BOTTLE

Donald B. Barrows, Richmond, Va., assignor to Necto Yeast Corporation, Richmond, Va.

Application October 28, 1931. Serial No. 41,549

Term of patent 3½ years

To all whom it may concern:

Be it known that I, DONALD B. BARROWS, a citizen of the United States of America, residing in Richmond, State of Virginia, have invented a new, original, and ornamental Design for Bottles, of which the following is a specification, reference being had to the accompanying drawing, forming part thereof, wherein:

I claim:

The ornamental design for a bottle as shown.

DONALD B. BARROWS.
